UNITED STATES PATENT OFFICE.

JAMES H. BROWN, OF OTTAWA, ILLINOIS.

OIL-CAN FOR OILING MACHINERY.

SPECIFICATION forming part of Letters Patent No. 290,206, dated December 18, 1883.

Application filed March 1, 1882. (Model.)

To all whom it may concern:

Be it known that I, JAMES H. BROWN, a citizen of the United States, residing in the city of Ottawa, in the county of La Salle and State of Illinois, have invented certain new and useful Improvements in Oil-Cans for Oiling Machinery; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of my invention is to provide a detachable funnel, which, when the oil-can is in use, shall rest upon the top of the can like a cap, covering the joint where the nozzle is screwed into the can, forming a part of the can, and thereby protecting the hands of the operator from oil escaping from the joint between nozzle and can, and which funnel can be slipped off, either before or after the nozzle is unscrewed, and inserted into the aperture in the top of the can from which the nozzle has been unscrewed, and the can is filled with oil poured through it. The funnel is made to fit tightly the base of the nozzle, and also to fit closely the aperture in the can, so that no screw or their appliance is necessary to hold it in place.

In the accompanying drawings, in which similar letters of reference indicate like parts, Figures 1 and 2 show in elevation and in section the funnel *a* as attached to the oil-can *b* when in use, and kept from working loose by the close connection of the parts and by the rubber ring *c*, which serves, also, as a receiver for oil leaking from the extremity of the nozzle. In Fig. 3 the nozzle *d* is shown as un-

screwed from the oil-can *b* and the funnel *a* partially removed. In Fig. 4 is shown the funnel *a* as inserted into the top of the oil-can *b* in use and the can being filled through it from the bottle of oil.

The mode of using the invention is as follows: The funnel (inverted) is slipped over the nozzle down upon the top of the oil-can, where it is held in place by the close proximity of the parts and by the rubber ring *c*, as shown in Fig. 1. Here the funnel covers the joint where the nozzle is screwed into the can, and protects the hands of the operator from the oil leaking through the joint.

To fill the can with oil, the funnel and rubber ring above it are slipped off, the nozzle unscrewed, and the funnel inserted into the mouth of the can, and oil poured through it into the can.

I claim as my invention—
1. A removable funnel capable of fitting the filling-orifice of an oil-can for oiling machinery, and fitting closely about the base of the filling-nozzle, and resting like a cap upon the body of the can when the can is in use, as and for the purpose set forth.

2. A removable funnel for oil-cans for oiling machinery, fitting closely about the base of the filling-nozzle, and resting like a cap upon the body of the can when in use, and a rubber ring, *c*, in combination, as and for the purposes set forth.

In testimony that I claim the foregoing I have hereunto set my hand and seal this 25th day of February, A. D. 1882.

JAMES H. BROWN. [L. s.]
